UNITED STATES PATENT OFFICE.

AMOS CALLESON, OF BROOKLYN, NEW YORK.

BOTTLE-SEALING MACHINE.

1,299,551.

Specification of Letters Patent.

Patented Apr. 8, 1919.

Application filed February 10, 1919. Serial No. 276,045.

To all whom it may concern:

Be it known that I, AMOS CALLESON, a citizen of the United States, residing at Brooklyn, in the county of Kings and State 5 of New York, have invented certain new and useful Improvements in Bottle-Sealing Machines, of which the following is a specification.

This invention relates to machines for affixing closures to containers by pressure. 10 One part of the invention consists in a novel closure affixing appliance. Another part of the invention consists in a novel combination of parts whereby on the affixing having been effected during the pressure stroke of the machine the closure affixing member or appliance may yield if the container exceeds 15 a certain height, thus to compensate for discrepancies in heights of bottles.

20 In the drawings,

Figure 1 shows partly in side elevation and partly in section sufficient of a machine embodying the invention to illustrate the same;

25 Figs. 2 and 3 are front elevations of the upper one of the coating pressure effecting means, showing two positions of the parts, the part *c''* being removed;

Fig. 4 is a horizontal section on about line 30 4—4, Fig. 1, certain parts being omitted.

Figs. 5 and 6 are plan views of the closure affixing appliance and plunger;

Fig. 7 is a plan, partly in section, of the part *c''*;

35 Fig. 8 is a plan, partly in section, of certain parts of the affixing appliance in the form thereof shown in Fig. 1;

Fig. 9 shows a modified form of the affixing appliance; and

40 Fig. 10 is a plan view of certain parts of the affixing appliance in the form thereof shown in Fig. 9.

It will be understood that it is immaterial 45 whether the bottle is elevated or the means carrying the affixing appliance descends in order to effect affixing. In the construction illustrated the latter is the condition assumed, the bottle support *a* being suitably secured to the frame *b* of the machine, and 50 the means *c* being moved up and down in the frame by any suitable means.

The means *c* includes a casting (hereinafter termed the abutment member) in two parts, body part *c'* and front part or cover 55 *c''* suitably held together, as by screws *d*. Body part *c'* has vertical grooves *e* engaged

by suitable guides (not shown) on the frame, and it is formed with a cavity *f* open at the front thereof and forming at the front opposite vertical guiding faces *g*, the upper 60 portion (*g'*) of one of which is in a plane slightly nearer than the lower portion thereof to the opposite guiding face *g* and joins said lower portion in an inclined cam abutment face *h*; body part *c'* also has a socket *i* 65 extending upwardly from the cavity and the parts *c'* and *c''* further form together a bearing *j*, vertically alined with the socket *i*. The cover part *c''* has a vertically inwardly 70 open groove *k*.

In telescoped relation to the abutment member is the affixing member, which includes a tubular stem *l* journaled and slideable vertically in the bearing *j* and formed 75 at its upper end with a head *m* and at its lower end with an enlargement or boss *n*. The head *m* bears against the bottom of cavity *f*, and it projects forward between the two guiding faces *g g*, its forward portion being about as wide as the distance between 80 *g' g*, so that when it is depressed (Figs. 1 and 2) the affixing member may rotate in bearing *j* a distance which is equal to the difference between the spacing of *g g* and that of *g' g'*; at *o* the head *m* has an inclined 85 cam abutment face to impinge the abutment face *h*. The head further has a cylindrical socket *p* opposed to socket *i*, and reaching forward from said socket to the front face of the head a vertical slot *q* formed with inclined cam faces *q'* and *q''* facing respectively upwardly and downwardly and pitched oppositely to the abutment faces *h* and *o*. To the boss *n* are secured the parts 90 having directly to do with the closure affixing, as will appear.

In the tubular affixing appliance is arranged the plunger *r* having a hardened ferrule *s* to bear on the closures and provided with a cylindrical head *t* which fits the socket *p* and has a forwardly projecting tongue *u* which projects into the slot *q* and keeps the plunger from turning; this tongue penetrates the slot *q* and fits the same and it has on its sides the inclined cam faces *u'* 100 *u''* pitched the same as the cam faces *q' q''* and respectively adapted to wipe against them when the plunger is moved vertical 105 relatively to the affixing appliance (compare Figs. 2 and 3). The normal position of the plunger is that shown in Figs. 1 and 2—depressed, and in this position it is held 110

by a spring v interposed between the plunger head t and the top of socket i .

- The type of instrumentality directly concerned in the attaching of the closure to the bottle head will usually afford a throat in which the shaping of the metal of the closure is performed and into or through which the lower end of the plunger projects. When the pressure stroke occurs, as soon as the bottle and superposed closure have become sufficiently entered into the throat to effect affixing of the closure to the head the plunger will have been elevated (relatively) in the affixing appliance to the position where its cam faces u u'' respectively register with the cam faces q q'' and (since the plunger cannot rotate, being held by engagement in the slot k) said appliance will be cammed around on its vertical axis so that it clears the abutment face h , whereupon, being unlocked, the affixing appliance yields with respect to the abutment member. On the return stroke cam face u' by bearing against cam face q' depresses the affixing appliance until the head of the latter clears the guiding face g' , whereupon cam face u' by wiping over cam face q' rotates the affixing appliance back to its original position, abutting abutment face h . Spring v of course maintains the necessary pressure for sealing and on the return stroke resets the parts to their normal positions (Figs. 1 and 2). It will be obvious that bottles of various heights may be accommodated, the extent of yield of the affixing appliance being more or less, according to the height of the bottle.

In the construction herein shown and described the lateral shifting of the affixing appliance to clear the abutment member at h is due not only to the camming action of the rising plunger (at u'' q'') but to the affixing appliance being normally impelled laterally by the inclined abutment faces h o as an incident of the bottle pressing the affixing appliance upwardly, the affixing appliance being free to respond to the camming action of said faces and shift laterally as soon as the cam faces u' q' begin to coincide.

My invention distinguishes from previous constructions in this art by virtue of the affixing member being itself shiftable laterally into and out of locking engagement with an abutment member: in previous constructions, as I am advised, the interlock between the abutment and affixing members has been afforded by a pawl or other third member. It also distinguishes from prior art known to me in respect to the fact that the shifting as between two abutting members in the means to support the affixing instrumentality and in order to allow one to clear the other to accomplish the yield is around a vertical axis.

A novel closure-affixing means is shown in Figs. 1, 8, 9 and 10, the same comprising an annular expandable throat-forming series of segments w , an annular cushion means x for the segments surrounding them and having at least the portion thereof opposite each segment composed of elastic plastic material (the drawing actually showing the cushion means continuously thereof formed of such material), and an annular unyielding abutment means for the cushion means, as the wall of the housing z , for example, surrounding the same, each said portion being free to expand lengthwise of the axis of the throat on compression thereof between the segments and abutment means when the former are expanded by the entering bottle head; to afford the freedom to expand stated the means x is shown in Figs. 1 and 9 as tapering in cross-section, thereby leaving, at x' , spaces above and below into which the plastic material can flow when the compression takes place. It is preferable, though not indispensable, that the three elements (segment series w , cushion x and wall y) fit each other. As shown in Fig. 8, to give a unitary character to the segments and cushion the latter may be surrounded by a metal band 4, and an interlock between band and cushion provided at 5. To prevent the segments pinching the rubber of the cushion, their outer vertical edges may be beveled off, as at 6, Fig. 8: or a metal lining provided, as at 7, Figs. 9 and 10, the same being a strap or band having its ends overlapping each other so as to be expansible.

Having thus fully described my invention, what I claim as new and desire to secure by Letters Patent is:

1. Means to affix a closure to a container by pressure including an abutment member, a closure affixing member upwardly abutting said abutment member but movable laterally to clear the same and being thereupon yieldable upwardly relatively thereto, and means, movable relatively to said closure affixing member and actuated by the work being operated upon, to move said closure affixing member laterally clear of the abutment member.

2. Means to affix a closure to a container by pressure including an abutment member, a closure affixing member upwardly abutting said abutment member and normally impelled laterally to clear the same and being thereupon yieldable upwardly relatively thereto, and means normally holding the closure-affixing member against lateral movement but movable by the work clear of the same.

3. Means to affix a closure to a container by pressure including an abutment member, a closure affixing member upwardly abutting said abutment member but movable laterally

to clear the same and being thereupon yieldable upwardly relatively thereto, one of the abutting portions of said members being an inclined cam face, and means normally holding the closure affixing member against lateral movement but movable by the work clear of the same.

4. Means to affix a closure to a container by pressure including an abutment member, a closure affixing member upwardly abutting said abutment member but rotative relatively thereto to clear the same and being thereupon yieldable upwardly relatively thereto, and means; movable relatively to said closure affixing member and actuated by the work being operated upon, to move said closure affixing member rotatively clear of the abutment member.

5. Means to affix a closure to a container by pressure including an abutment member, a closure affixing member upwardly abutting said abutment member but normally impelled rotatively relatively thereto to clear the same and being thereupon yieldable upwardly relatively thereto, and means normally holding the closure affixing member against rotation but movable by the work being operated upon to clear the same.

6. Means to affix a closure to a container by pressure including an abutment member, a closure affixing member upwardly abutting said abutment member but rotative relatively thereto to clear the same and being thereupon yieldable upwardly relatively thereto, one of the abutting portions of said members being an inclined cam face, and means normally holding the closure affixing member against rotation but movable by the work being operated upon to clear the same.

40 7. Mechanism to affix a closure to a container by pressure including, with the affixing instrumentality, means to support the latter including a plurality of members one abutting upwardly against the other and one being rotative on a vertical axis to clear the other and permit said upwardly abutting member to yield upwardly relatively to the member abutted thereby, and means, movable relatively to said instrumentality and actuated by the work being operated upon, to move the rotative member clear of the other member.

8. Mechanism to affix a closure to a container by pressure including, with the affixing instrumentality, means to support the latter including a plurality of members one abutting upwardly against the other and one being normally impelled rotatively on a vertical axis to clear the other and permit said upwardly abutting member to yield upwardly relatively to the member abutted

thereby, and means normally holding the rotatively impelled member against rotation but movable by the work being operated upon to clear the same.

65

9. Means to affix a closure to a container by pressure including an abutment member, a closure affixing member having a vertical sliding connection with the abutment member and shiftable laterally into upwardly abutting engagement therewith to prevent upward yielding of said affixing member relatively to the abutment member, and a vertically movable work controlled plunger controlling the lateral shifting of said closure affixing member.

10. Means to affix a closure to a container by pressure including an abutment member, a closure affixing member having a vertical sliding connection with the abutment member and rotative on a vertical axis into upwardly abutting engagement therewith to prevent upward yielding of said affixing member relatively to the abutment member, and a vertically movable work controlled plunger controlling the rotary shifting of said closure affixing member.

80

11. Means to affix a closure to a container by pressure including an abutment member, a closure affixing member having a vertical sliding connection with the abutment member and shiftable laterally into and out of upwardly abutting engagement therewith, and a vertically movable work-controlled plunger having means on vertical movement thereof to cam and thus shift the affixing member laterally.

95

12. Means to affix a closure to a container by pressure including an abutment member, a closure affixing member having a vertical sliding connection with the abutment member and shiftable rotatively into and out of upwardly abutting engagement therewith, and a vertically movable work controlled plunger having means on vertical movement thereof to cam and thus shift the affixing member rotatively.

105

13. In combination, an annular expandible throat-forming series of segments, an annular cushion means for the segments surrounding them and having the portion thereof opposite each segment composed of elastic plastic material, and an annular unyielding abutment means for the cushion means surrounding the latter, each said portion being free on compression thereof between the expanded segments and abutment means to expand lengthwise of the axis of the throat.

110

In testimony whereof I affix my signature.

115

AMOS CALLESON.
